SMOKERS' STAND

William T. Arthur, Raleigh, N. C.

Application March 16, 1950, Serial No. 8,560

Term of patent 3½ years

(Cl. D35—2)

To all whom it may concern:

Be it known that I, William T. Arthur, a citizen of the United States of America, residing at Raleigh in the county of Wake and State of North Carolina, have invented a new, original, and ornamental Design for Smokers' Stand, of which the following is a specification, reference being had to the accompanying drawing, forming a part thereof, wherein:

The sole figure is a perspective view of a smokers' stand, showing my new design.

I claim:

The ornamental design for a smokers' stand, as shown.

WILLIAM T. ARTHUR.
